UNITED STATES PATENT OFFICE

138,683

DESIGN FOR A BLASTING CAP FASTENER

Fritz Hermann Rolfes, Johannesburg, Transvaal,
Union of South Africa

Application May 9, 1944, Serial No. 113,522

In the Union of South Africa March 16, 1944
Term of patent 14 years

(Cl. D30—1)

To all whom it may concern:

It is known that I, Fritz Hermann Rolfes, a British subject, residing at Johannesburg, in the Province of the Transvaal, Union of South Africa, have invented a new, original, and ornamental Design for a Blasting Cap Fastener, of which the following is a specification, reference being had to the accompanying drawing, forming part thereof.

Figure 1 is a perspective view of a blasting cap fastener showing my new design; and

Figure 2 is a side elevational view thereof.

I claim:

The ornamental design for a blasting cap fastener, as shown.

FRITZ HERMANN ROLFES.
